CLAIM

The ornamental design for a double check valve, as shown and described.

DESCRIPTION

FIG. 1 is a top perspective view of a valve according to a first embodiment of a valve in accordance with the present invention;

FIG. 2 is a left side view of the valve seen in FIG. 1; FIG. 3 is a right side view of the valve seen in FIG. 1; FIG. 4 is a bottom view of the valve seen in FIG. 1; FIG. 5 is a front view of the valve seen in FIG. 1; FIG. 6 is a top view of the valve seen in FIG. 1; FIG. 7 is a rear view of the valve seen in FIG. 1; FIG. 8 is a top perspective view of a second embodiment of a valve in accordance with the present invention; FIG. 9 is a left side view of the valve seen in FIG. 8; FIG. 10 is a right side view of the valve seen in FIG. 8; FIG. 11 is a bottom view of the valve seen in FIG. 8; FIG. 12 is a front view of the valve seen in FIG. 8; FIG. 13 is a top view of the valve seen in FIG. 8; and, FIG. 14 is a rear view of the valve seen in FIG. 8. The words and numbers appearing on the valve do not form an essential part of the design, apart for their location.
